BINAURAL ADDRESS SYSTEM

Irl R. Goshaw, Nutley, N. J., assignor to Wired Radio, Inc., New York, N. Y., a corporation of Delaware

Application May 4, 1932, Serial No. 609,061

5 Claims. (Cl. 179—1)

This invention relates to electrical transmission and reproducing systems, and particularly to public address and recording systems for large auditoriums and outdoor areas.

6 An object of the invention is to transmit to a group of listeners a source of sound in its natural aspect.

Another object of the invention is to maintain directional effects in a sound source for a large 10 audience when the sound is reproduced electrically at different points.

A still further object of the invention is to provide an amplification system having varying amounts of amplification in accordance with the 15 amplitude or strength of the input signal.

Binaural transmission systems for recording and reproducing in talking motion pictures and public address systems are well known in the art. Such systems obtain binaural aspects by the 20 phase and amplitude discrimination between a signal arriving at microphones or other pick-up devices positioned to correspond to the ears of a person. It has been found, however, in the practical use of such systems that it is difficult 25 to distinguish the direction of a source of sound solely by phase displacement, and that where a high percentage of successful tests were made, the sense of direction was obtained chiefly by amplitude variations arriving at the listener.

30 The present invention utilizes the fact that amplitude is the principal factor in direction determination. The invention contemplates means for emphasizing this effect to such an extent that an entire audience will be aware of the binaural 35 aspect regardless of the position of any one person with respect to the sound source or reproducers. The means to produce this differential in amplification is an amplifying circuit which varies its amplification constant with amplitude 40 input, a preferable type of circuit being described hereinafter. Two such amplifying circuits are fed from two groups of pick-up devices positioned at the sides or ends of the action space, and feed 45 groups of reproducing devices such as loud speakers located in nearby positions, the binaural effect being so emphasized that each listener in a large audience will not only be able to receive the signal at the proper volume but will also be definitely 50 aware of its direction. Such a system is applicable 55 to public address systems as stated above, and also to sound recording and reproduction for talking motion pictures.

The invention will be more fully understood by 60 reference to the following specification read in conjunction with the accompanying drawing in which:

Fig. 1 is a diagrammatic drawing of the positioning of pick-up and sound reproducing devices 65 in accordance with the invention; and

Fig. 2 is a schematic drawing of the amplifiers employed in the arrangement of Fig. 1.

Now referring particularly to Fig. 1 an action area 5 which may constitute a stage or platform in an auditorium or outdoors, has positioned at each end or corner thereof, a plurality of pick-up devices 6 and 7. These pick-up devices may extend partially along the front portion of the area or in any suitable positions to intercept signals advantageously. Each group of devices or microphones are connected to the input of similar amplifiers 9 and 10 which feed a plurality of groups of loud speakers 11 and 12. These speakers may be positioned behind curtains or in the partitions of the auditorium, and for outdoor work may be mounted upon supporting structures in accordance with well known public address system practice.

Two sources of sound, S_1 and S_2 have been shown within the area 5, it being obvious that the source S_1 will produce at the group of pick-up 6 a much higher volume level than at group 7, the amplitude of the signal varying in accordance with the square law minus a certain absorption constant depending upon the medium through which the sound is projected. Similarly, the source S_2 will produce in the microphones 7 a volume level greater than that in the microphones 6 in accordance with the same law. Now, when each amplifier produces proportional amplitudes in the reproducing devices there will occur to those listeners seated near either group of loud speakers, no change whatever with respect to direction. These listeners will always receive sound from the same group of speakers regardless of amplitude variation in the pick-up devices because of their proximity to the speakers. The present invention corrects this defect in present binaural systems by producing a differential amplification in the proper direction in accordance with the strength of the signal which emphasizes the desired effect and consequently produces the binaural aspects for the entire audience.

Now referring to Fig. 2 an amplifier system is shown having two stages, it being understood that more stages can be added in accordance with well known amplifier practice. A sound signal is translated into electrical currents by a pick-up device or microphone 15. The microphone is in a series circuit including the primaries of input transformers 16 and 17 and a source of energy 18. The output of the transformer 16 is impressed upon a vacuum tube 19 of the screen grid variable mu type well known in the art in which the control grid bias varies the amplification factor of the tube without distortion. In the input circuit of the tube 19 is a biasing resistance 20 which controls the amount of operating bias potential on this tube, the fixed potential being determined 115

by a battery 21. The output circuit of tube 19 includes the primary of inter-stage transformer 22 and a source of polarizing potential 23 which also provides a polarizing potential for the screen 5 grid or second anode 24. Of course the potential for the element 24 may also be furnished by a separate energy supply.

The output of transformer 22 is impressed upon the usual type of screen grid tube 26 this tube 10 not having the variable mu characteristic. The tube 26 has thereon a fixed bias from a source 27 and an anode polarizing potential 28. The output of the tube 26 is through an output transformer 29, the output being impressed upon a 15 reproducing device such as a loud speaker 30. In this stage, however, the screen grid element 31 of the tube 26 is connected so as to have thereon a variable voltage in accordance with the input of the amplifying system, but has its initial operating point fixed by a voltage source 32.

Now returning to the input circuit of the amplifier, the signal currents produced in the microphone 15 are transmitted through the output transformer 17 to a rectifying device 33 of any 25 suitable type followed by a filter 34 which reduces the pulsating currents to a smooth direct current. The output of the filter is connected to the screen grid element 31 of tube 26 and also to one terminal of the resistance 20 of the tube 30 19. The voltage and current obtained from the filter 34 will be proportional to the level of the input signal. This energy impressed on the screen grid 31 will change the amplification factor of the tube 26 in accordance with the input signal, 35 by shifting the operation of the tube from one characteristic to another having different slopes. That is, the stronger the signal the higher the amplification factor and since the tube is always operating on the straight portion of one of its 40 characteristics, distortion will be eliminated. This same result is accomplished by impressing energy from the filter 34 on the resistance 20 of the tube 19 which changes the amplification constant of the tube in the desired direction. For 45 instance, the fixed bias placed upon the tube 19 gives it a low mu which is increased as the bias is removed by the energy from the filter 19. That is, should the signal be of small amplitude on arriving at the microphone 15, the amplification 50 system will provide a certain amount of overall gain which will be low compared with the gain in the system at a higher input level.

By the use, therefore, of two circuits of the 55 above type at positions 9 and 10 in Fig. 1, a signal occurring at S_1 will produce in the loud speakers 11, a volume level much greater proportionally than that produced by the same signal in the loud speakers 12. In fact, the source S_1 depending upon its position, will practically be reproduced 60 solely at the loud speakers 11 and not at the loud speakers 12, so that those listeners in the neighbourhood of speakers 12 will recognize the signal as originating at the point S_1 and not at the other end of the action area due to the proximity 65 of the speakers 12.

By employing such a pick-up system for recording and by a similar arrangement of reproducing devices for the projection of talking pictures, the binaural aspects are obtainable. When the 70 recording and reproducing amplifiers are both of the type disclosed above, the binaural effect is doubly emphasized.

The differential amplifying system has been illustrated in one particular modification, but it is 75

to be understood that other uses will suggest themselves to those skilled in the art, such equivalent systems being considered within the scope of the appended claims.

What is claimed is:

1. In a binaural public address system supplying 80 a listening area, the combination of a plurality of sound pickup devices in the locality of a source of sound, a plurality of sound reproducers arranged on certain portions of the border of said area, and volume expanding means positioned intermediate said devices and said reproducers, said means having an amplifying factor which increases with an increase in signal input to render emphasis to amplitude discrepancies at said devices.

2. In a binaural system for a listening area, the combination of a plurality of microphones positioned at different points for detecting the 85 same sound source, a plurality of speakers arranged outside said area and directing sound into said area, and a plurality of volume expanding amplifiers positioned intermediate said microphones and said speakers, said amplifiers having an amplifying factor which increases with 90 increased volume level at the input of said microphones to provide a directional effect for listeners at substantially all positions within said area.

3. In a binaural reproducing system for a listening area, a microphone, a loud speaker positioned 95 on the border of said area at a distance from said microphone, a volume expanding amplifier intermediate said microphone and said speaker, a second microphone, a second loud speaker positioned on another portion of the border of said 100 area at a distance from said second microphone, another volume expanding amplifier intermediate 105 said second microphone and said second speaker, said microphones being positioned to receive sound from a common source and said speakers 110 directing sound into said area, and means for varying the amplification factor of said amplifiers in accordance with the volume of the sound reaching said microphones, the effective operating speakers being determined by the microphone 115 receiving the larger amplitude of said sound.

4. In a binaural reproducing system for a definite listening area, a sound reproducer positioned 120 at one point of said area directing sound into said area, a second sound reproducer positioned at 125 another point of said area directing sound into said area, a volume expanding amplifier connected to each of said reproducers, and sound pick-up devices feeding said amplifiers, said devices receiving varying amplitudes of sound from 130 a sound source in the sound pick-up area, the gain of said amplifiers being arranged to effectively operate the sound reproducing device connected to the pick-up device receiving the larger amplitude.

5. In a binaural system for a listening area, a sound reproducer at a position in said area, a second reproducer at another position in said area, a microphone in a sound pick-up area connected 135 to one of said reproducers, a second microphone 140 in said pick-up area connected to the other of said reproducers, said microphones being positioned in a sound pick-up area, and volume expanding means intermediate said microphone and said reproducers for effectively reproducing the 145 sound from said area at the respective reproducer in accordance with the microphone energized in said sound pick-up area.
